(57) **CLAIM**

The ornamental design for a water timer, as shown and described.

DESCRIPTION

FIG. 1 is a perspective view of a water timer showing our new design;

FIG. 2 is a left side elevational view showing the design for the water timer of FIG. 1;

FIG. 3 is a right side elevation view showing the design for the water timer of FIG. 1;

FIG. 4 is a front elevational view showing the design for the water timer of FIG. 1;

FIG. 5 is a rear elevational view showing the design for the water timer of FIG. 1;

FIG. 6 is a top plan view showing the design for the water timer of FIG. 1; and,

FIG. 7 is a bottom plan view showing the design for the water time of FIG. 1.

The broken line showing of portions of the water timer including the diamond pattern on the bottom portion of the timer is included for illustrative purposes only and forms no part of the claimed design.
